APPARATUS FOR WASHING OILS WITH AN
IMMISCIBLE WASH LIQUID

Charles E. Ayres, Phillips, Tex., assignor to Phillips Petroleum Company, a corporation of Delaware

Application September 9, 1946, Serial No. 695,797

3 Claims. (Cl. 210—47)

1

This invention relates to the treatment of oils. In one of its more specific aspects it relates to the treatment of oils by washing with liquids immiscible with the oils, such as water and apparatus therefor.

Water washes are frequently used in various hydrocarbon oil treating processes to remove chemical salts, unreacted and partially reacted acids or alkalis carried in solution or in suspension in the oil. Such washing operations are frequently performed in tanks containing the wash water and equipped with perforated distribution spiders.

The object of the perforated spider is to disperse the incoming oil into many small streams which, in passing up through the water, expedite contacting between the water and oil. These perforations are ordinarily small in consideration of the volume of oil to be distributed so as to obtain a jet effect and thereby more efficient washing. However, in many instances I have found that due to the high oil concentration at the perforations solid salts are often deposited on or in the orifices resulting in a restriction or even stoppage of flow.

An object of my invention is to provide means for the prevention of orifice plugging in such oil-water washing operations.

Another object of my invention is to provide an apparatus for use in combination with a distribution spider to prevent plugging of the spider orifices.

Still another and more specific object of my invention is to provide means to assist in preventing the precipitation of salts in wash tank distribution spiders at points of contact between oil and water.

Still other objects and advantages of my invention will be apparent to those skilled in the art from a careful study of the following description and attached drawing which respectively describes and illustrates a preferred embodiment of my invention.

Figure 1 is a diagrammatic illustration of one form of my oil-water washing apparatus. Figure 2 is a diagrammatic sectional view of my jet suction washing apparatus.

Referring now to the drawing an elongated cylindrical tank 11 may be horizontally disposed and adapted to carry several pipe connections as a connection 12 for the introduction of oil to be water washed, a connection 13 for removal of washed oil and a connection 14 carrying a valve 15 for the introduction and removal of wash water.

However, such a wash tank need not be horizontally disposed as illustrated, but may be vertically disposed, in which case the tank may substantially stand "on end." And further, the tank may be any other shape or form, providing it is

2

adapted to such a 2-liquid phase washing operation.

The inlet pipe 12 extends through the tank wall and nearly to the bottom. At its lower extremity is a T 16 adapted to carry two side arms 17. These arms or pipes 17 have perforations 18 along the bottom sides as shown. This structure so far described constitutes a form of oil-water washing apparatus of the prior art. I have found that in using such a water wash apparatus the openings 18 in many cases acquire salt deposits which restrict liquid flow therethrough, and after prolonged operation many of the openings may become plugged or substantially so. Under such conditions an oil transfer pump will have to operate at a markedly higher pressure in order to pump oil to be washed at a given rate through the wash spider.

I have found that by inserting a constricting orifice or jet 19 and providing openings 20 in each of the arms 17 of the spider that salt precipitation at the orifices 18 was substantially eliminated.

Each jet 19 may be of conventional jet construction, or may be such a piece of apparatus as a "reducing swedge." When a swedge is used as a jet producing means, the body of the swedge must be adapted for installation in such a pipe, as pipe 17 and the pipe-swedge assembly then attached to the T 16. In such an assembly a swedge may be selected such that it will slide into the pipe in which it is to serve as a jet. The small end is inserted first, and the swedge pushed in sufficiently far that heat from welding at weld 21 may not interfere with threads 22. Threads 22 are for connecting the spider arm pipes 17 to the T 16.

The openings 20 may preferably have been made in the pipes 17 prior to the installation of the swedge or jet members 19. These openings may be located with respect to the constricted end of the jet members 19 approximately as indicated in the drawing. It is intended in the operation of my device that upon passage of liquid through the constricted end of the jet member a second liquid will be drawn in through the openings 20. This structure may also be brought of as a venturi type assembly.

50

Operation

In the operation of my apparatus for washing one liquid with a second liquid wherein an insoluble precipitate forms in perforations of the spider arm orifices, the tank 11 may be about half filled with a wash liquid, for example, water. The liquid to be washed enters through the inlet pipe 12, flows through the jets 19 and finally leaves the spider arms through the perforations 18. In passing through a jet 19, suction is created and wash liquid enters the pipe 17 through the openings 20.

The openings 20 are intended to permit relatively large volumes of wash liquid to enter so that the relative volume of oil passing through the openings 18 is small, that is, the ratio of the volumes of oil to wash liquid is small. In this manner precipitation of insoluble matter at openings 18 is held to a minimum or substantially eliminated.

Example

In the sweetening of sour hydrocarbon oils by contacting with an aqueous cupric chloride solution, the copper chloride treated oil is given an after wash with an aqueous sodium sulfide solution. It has been found advantageous in some instances to follow this sulfide wash with a water wash. When using a water wash apparatus consisting of a tank partly filled with wash water and containing a distribution spider as hereinbefore described, I have found that many of the orifices in the distributor arms became partly or entirely plugged with deposited salts. After prolonged operation so many orifices became restricted in effective area that the oil pump pressure had to be increased to a prohibitive pressure in order to pass the daily throughput of oil.

When pump pressures reached a certain value, the washing step was bypassed, and the spider arms removed and the openings cleaned of the scale deposits. During this cleaning operation oil was passed from the sodium sulfide washing unit through a heat exchanger and into a fractionation unit and deposition of scale in the heat exchanger and reboiler coils of the fractionator occurred. Such scale deposition on heat exchange surfaces adversely influences heat exchange and obviously is to be avoided.

In a gasoline sweetening operation followed by sulfide and water washes, I installed my jet 19-orifice 20 assembly in each of the distribution scale deposits. During this cleaning operation substantially no orifice (18) plugging had occurred by deposition of scale.

In this installation the water wash tank was a horizontally disposed tank 10 feet in diameter by 36 feet long. The spiders (pipes 17) were 6 inch pipes having $\frac{3}{8}$ inch perforations along the bottom. Two such pipes were connected to a T at the end of the oil inlet pipe. The jets were $1\frac{1}{2}$ inch in diameter and six openings (20) surrounded each jet. The gasoline so washed in this unit was 600,000 gallons per day.

As mentioned hereinbefore, the water wash tank need not be of the form and disposition as illustrated in the drawing, but may be vertically disposed if desired. The tank may also be of a "pan" type, that is, a cylindrical tank of relatively large diameter and short axial length. In this latter case there may be four spider (17) pipes, or a manifold system, all depending on the size of the tank and on capacity requirements.

Materials of construction will be determined by the products and reagents handled.

It will be obvious to those skilled in the art that many variations and alterations in my washing apparatus may be made and yet remain within the intended spirit and scope of my invention.

5 Having disclosed my invention, I claim:

1. Apparatus for washing oils with an immiscible wash liquid comprising, in combination, a container for holding a wash liquid, an oil inlet pipe extending into said container, a perforated oil distribution spider positioned at the bottom portion of said container, means including a conduit having a tapered portion mounted within said spider for passing oil from said inlet pipe through the perforated portion of said spider, said spider having an opening adjacent the reduced portion of said conduit whereby a flow of oil through said conduit causes wash liquid to enter the spider through said opening, the wash liquid in said spider preventing precipitation of insoluble matter at the perforations in said spider.
- 10 2. Apparatus for washing oils with an immiscible wash liquid comprising, in combination, a container for holding a wash liquid, a perforated conduit positioned in the lower portion of said container, means for introducing oil into said conduit including a jet supported within the conduit and having a portion of reduced diameter, said conduit having an opening adjacent said portion of reduced diameter whereby flow of oil through said jet means causes wash liquid to flow through said opening by venturi action, the wash liquid in said conduit preventing the deposition of solid matter at the perforated portions of said conduit.
- 15 3. Apparatus for washing oils with an immiscible wash liquid comprising, in combination, a tank adapted to contain a wash liquid, an oil distribution conduit in the lower portion of said tank, said conduit having a series of circumferentially disposed openings adjacent one end thereof and a series of perforations spaced from said openings and of relatively small size as compared with said openings, a jet inserted in said end of the conduit having an outlet portion for directing oil into the perforated part of said conduit, said jet having a portion of reduced diameter adjacent said openings, and means for delivering oil to the inlet portion of said jet.

Certificate of Correction

Patent No. 2,531,547

November 28, 1950

CHARLES E. AYRES

It is hereby certified that error appears in the printed specification of the above numbered patent requiring correction as follows:

Column 2, line 47, for the word "brought" read *thought*; column 3, line 40, strike out "scale deposits. During this cleaning" and insert instead *arms 17, and after a 30-day period of;*

and that the said Letters Patent should be read as corrected above, so that the same may conform to the record of the case in the Patent Office.

Signed and sealed this 6th day of March, A. D. 1951.
